Specification for Design.

Patented Oct. 15, 1918.

Application filed March 4, 1916. Serial No. 82,251. Term of patent 14 years.

To all whom it may concern:

Be it known that I, CHARLES WACHTEL, a citizen of the United States, residing in Jamaica, county of Queens, and State of New York, have invented a new, original, and ornamental Design for Cases for Flash-Lights, of which the following is a specification, reference being had to the accompanying drawing, forming a part hereof.

In the drawing, Figure 1 is a perspective view of the case, showing the front and top thereof;

Fig. 2 a similar view showing the back and the bottom thereof; and

Fig. 3 a top view of the case.

I claim:

The ornamental design for a case for a flash-light, as shown.

CHARLES WACHTEL.
